UNITED STATES PATENT OFFICE.

WILLIAM A. STULL, OF FORT DEFIANCE, WEST VIRGINIA.

RAILWAY-TRACK SWITCH.

1,152,573.

Specification of Letters Patent

Patented Sept. 7, 1915.

Application filed April 19, 1915. Serial No. 22,457.

To all whom it may concern:

Be it known that I, WILLIAM A. STULL, a citizen of the United States, residing at Fort Defiance, in the county of Fayette and State of West Virginia, have invented certain new and useful Improvements in Railway-Track Switches, of which the following is a specification, reference being had to the accompanying drawings.

10 My present invention relates to new and useful improvements in railway track switches and has more particular reference to switches of the type employed in connection with narrow-gage tracks in coal or other mines, wherein a brakeman usually controls the movement of each car.

One of the primary objects of the invention is to provide a switch operating mechanism which may be employed in connection 20 with a switch of the trailing type, so that the passing of a car or train of cars through the switch, from the siding on to the main track, will not necessitate the manual shifting of the switch controlling lever, the mechanism being so designed that the point rail may yield to permit the car wheels to pass from the siding tracks on to the main track and to automatically return the point rail to a closed position for the main track, as 30 soon as the cars pass on to the same.

A further object of the invention is to provide a switch operating mechanism of the above type in which the shifting lever for the point rail is mounted for movement 35 in a path parallel to the main track so that the lever may be readily operated from the front of a motor gatherer.

Another object is to so construct the operating mechanism that the point rail shifting lever and consequently the point rail itself will be yieldably held in either open or closed track position when the shifting lever has been adjusted.

A further object and one of importance, 45 is to construct the switch mechanism with such regard to proportion, number and arrangement of parts, that it may be cheaply manufactured, will be durable and efficient in service and may be readily applied to a point rail of a track.

The above, and other incidental objects of a similar nature which will be hereinafter more specifically treated are accomplished by such means as are illustrated in the accompanying drawings, described in the following specification, and then more particu-

larly pointed out in the claims which are appended hereto and form part of this application.

With reference to the drawings, wherein 60 there has been illustrated the preferred embodiment of this invention, as it is reduced to practice, and throughout the several views of which similar reference numerals designate corresponding parts, Figure 1 is 65 a top plan view showing the switch mechanism connected to the point rails at the junction of the main track and siding; Fig. 2 is a detail section on the line 2—2, Fig. 1; Fig. 3 is a detail perspective view of the 70 operating rod and the lower portion of the shifting lever and the link which connects the rod and lever; and Fig. 4 is a detail perspective view of the lever which controls the toggle arm and the bracket by which 75 it is attached to the supporting frame or stand.

As best disclosed in Fig. 1, the switch stand and switch mechanism is adapted to be secured upon the outer ends of the track 80 ties A, whereby it may be operatively connected to the point rails B which lead from the main track rails C to the siding rails D.

The switch stand is preferably formed in the nature of a rectangular frame which 85 includes the parallel side bars 10 and the transverse connecting bars 11, one of which is arranged at the center of the side members and the other two of which are secured at the terminals thereof. This frame 90 constituted by the members 10 and 11 is secured by spikes or equivalent fastening devices upon the rails at the outer terminals thereof and immediately adjacent the main track, as disclosed in Fig. 1.

Rising from the stand or frame is a supporting bridge in which the shifting lever 12 is pivoted. The supporting bridge consists of a pair of substantially semi-circular bars 13 which are arranged in parallel 100 spaced relation to each other and are provided at their lower terminals with the outwardly extending lugs or plates 14, through which bolts, rivets or equivalent fastening devices are passed for securing the members 13 to the side bars 10 of the supporting stand. In connecting the shifting lever to the point rail, I employ an operating rod 15 and a bell crank lever 16. The operating rod 15 is preferably formed from a single 105 rod of steel, or the like, which is bent adjacent one terminal, forming an arm 17 which

is disposed in parallel spaced relation to the main portion of the rod. The rod is disposed for sliding movement over the side bars 10 and is held against transverse movement with respect to the shifting lever by means of the bars 13 which, as will be seen upon reference to Fig. 1 constitute, not only a support for the shifting lever, but also a guide for the operating rod during the reciprocal operation of this member. The free end of the arm 17 is connected to the lower terminal of the shifting lever by means of a link 18 which may be of any desired construction.

15 The bell crank lever 16 is mounted upon a fixed pivot 19 which is secured to the intermediate bar 11 and passes through the bell crank lever at the junction of the two arms 20 and 21 thereof. The arm 20 is connected by a pivotal link 22 and rod 23, to the point rails B, as best disclosed in Fig. 1. The arm 21 is pivotally connected by a pivot pin 24 to a link 25. This link 25 is pivotally connected at its rear end by a pin 26 to the rod 15. The pivot 24 further serves to connect the inner end of the toggle arm 27 to the bell crank lever and to the operating rod.

10 The outer end of the toggle arm 27 is pivotally connected to a lever 28, one end of which is pivotally secured within a bracket 28' to the supporting stand and the other terminal of which is engaged by a contractile helical spring 29. The member 29 extends transversely with respect to the operating rod and is secured at its inner end by a bracket 30 which is fastened upon the member 10.

15 It is now to be explained that the spring 29 normally exerts a pull upon the free end of the lever 28, thereby normally tending to draw the free end of this member toward the operating rod. Since the shifting lever, when adjusted to either open or close the point rails, carries the pivot 24 beyond the transverse line connecting the pivots 19 and 26, when adjusted to either open or close the point rails B, it is obvious that the arm 21 of the bell crank lever and the toggle 27 will be diagonally arranged with respect to the operating rod and that the distance between the pivotal points 19 and 26 will be less than the combined length of the members 21 and 27. Thus the spring 29 will act, when the shifting lever has been adjusted to either open or close the point rails, to draw the free end of the lever 28 toward the rod and thus resist the further adjustment of the lever.

20 In reduction to practice, it has been found that the form of this invention illustrated in the drawings and referred to in the above description as the preferred embodiment is the most efficient and practical; yet realizing that the conditions concurrent with the

adoption of this device will necessarily vary, it is desirable to emphasize the fact that various minor changes in the details of construction, proportion and arrangement of parts may be resorted to, when required, 70 without sacrificing any of the advantages of this invention, as defined by the appended claims.

What is claimed is:—

1. In a switch mechanism, the combination with a point rail, of a shifting lever, a bridge member pivotally supporting the lever, an operating rod mounted for sliding movement through the bridge member and freely connected to the shifting lever, a bell 75 crank lever having a fixed pivot, one arm of said bell crank lever being connected to the operating rod, means freely connecting the other arm of the bell crank lever to the point rail, and yieldable means for normally holding the operating rod in adjusted position. 80

2. In a switch mechanism, the combination with a point rail, of a shifting lever, a bridge member pivotally supporting the lever, an operating rod mounted for sliding 85 movement through the bridge member and freely connected to the shifting lever, a bell crank lever having a fixed pivot, one arm of said bell crank lever being connected to the operating rod, means freely connecting the other arm of the bell crank lever to the point rail, a toggle arm pivotally connected to the bell crank lever and to the operating rod, a lever pivoted for movement at its free end toward and away from the operating rod, 90 and yieldable means normally drawing the free end of the lever toward the operating rod, whereby the toggle arm is yieldably maintained in position to resist the movement of the operating rod. 100

3. In a switch mechanism, the combination with a point rail, of a shifting lever, a bridge member pivotally supporting the lever, an operating rod mounted for sliding movement through the bridge member and 105 freely connected to the shifting lever, means operatively connecting the rod to the point rail, and yieldable means for normally holding the operating rod in adjusted position. 110

4. In a switch mechanism, the combination with a point rail, of a shifting lever, a bridge member pivotally supporting the lever, said bridge member including spaced, substantially semi-circular bars, the lever being pivoted between the bars at the upper 115 portions thereof, an operating rod mounted for sliding movement between the bars of the bridge, and freely connected to the shifting lever, means operatively connecting the rod and point rail, and yieldable means for 120 holding the rod in adjusted position. 125

5. In a switch mechanism, the combination with a point rail, of a shifting lever, a bridge member comprising spaced, substantially semi-circular bars, the lever being piv- 130

- totally supported between the bars, an operating rod slideable between the bars, one terminal of the rod being re-bent and extended in parallel spaced relation to the body of the 5 rod, a link pivotally connecting said re-bent terminal of the rod with the shifting lever, means operatively connecting the rod and point rails, and yieldable means for maintaining the rod in adjusted position.
- 10 6. In a switch mechanism, the combination with a point rail, of a bridge member, a shifting lever pivoted in the bridge, and operating rod mounted for sliding movement through the bridge member, means op- eratively connecting the rod and point rail, 15 a lever pivoted at its one terminal adjacent the bridge member, a toggle pivotally connecting the rod and lever, and yieldable means connected to the free end of the lever for normally drawing said free end of the 20 lever toward the rod, whereby the toggle resists the movement of the operating rod.

In testimony whereof I hereunto affix my signature in the presence of two witnesses.

WILLIAM A. STULL.
